UNITED STATES PATENT OFFICE.

JAMES M. McDONOUGH AND TONY J. STEVENS, OF GALVESTON, TEXAS, ASSIGNEES TO THE NEILAN CORPORATION, OF HOUSTON, TEXAS, A CORPORATION OF TEXAS.

ADJUSTABLE PUMP PACKING.

Application filed November 12, 1923. Serial No. 674,181.

To all whom it may concern:

Be it known that we, JAMES M. McDONOUGH and TONY J. STEVENS, citizens of the United States, residing at Galveston, 5 Galveston County, Texas, have invented a certain new and useful Improvement in Adjustable Pump Packings, of which the following is a specification.

Our invention relates to an improvement 10 in packing means for pumps of the reciprocating type and pertains particularly to the means by which the packing is expanded when it becomes worn due to wear.

An object of the invention is to provide 15 means whereby the packing means outside the plunger may be expanded as desired by merely lowering the plunger beyond its ordinary stroke and forcing the retaining gland downwardly against the packing.

Another object is to provide means for 20 automatically retaining the gland in depressed position.

Referring to the drawing herewith, forming 25 a part of this specification, Fig. 1 is a central longitudinal section through a pump barrel and plunger embodying my invention. Fig. 2 is a top plan view of the packing locking device; and Fig. 3 is a broken detail illustrating a portion of said locking means.

Like numerals of reference designate like 30 parts in all the views.

In the drawing the pump barrel 1 is shown as being connected at its upper end to the tubing 2. At its lower end it is reduced 35 slightly in diameter and threaded at 3 to make a flush joint with a nipple 4, the wall of which is thicker than that of the pump barrel to provide a shoulder at 5 to receive the radial flange 6 upon the upper end of 40 the packing sleeve 7 fitting within the said nipple. The lower end of the nipple is threaded internally to receive the tubing 8 adapted to connect the nipple and pump barrel with the foot valve—not shown.

The upper end of the packing sleeve 7 45 forms a seat to receive the packing means which consists, in this embodiment, of a compressible wear resisting ring 9. Said packing is held downwardly in its seat by a gland 50 made up of a sleeve 10, resting thereon and fitting closely against the plunger.

The said sleeve is reduced in external diameter at 11 and tapered upwardly to provide a seat 12 for a set of four arcuate slips 55 or dogs 13.

Said slips have connection at their upper ends with a flat ring or washer 14. Set screws 15 passing through said ring are secured in said jaws as shown in Fig. 2. The openings 16 in said ring are oblong radially of the ring to allow expansion or contraction of said slips in use, the ring serving to retain them in assembled position. The jaws are provided with upwardly inclined teeth 17 and, to receive these teeth, the inner surface of the upper end of the barrel 1 may be also toothed at 18, said teeth being downwardly inclined.

The plunger comprises a smooth cylindrical barrel 19 which is understood as having the usual valve at the lower end thereof. The barrel 19 is threaded internally at 20 for attachment to a head 21 having a passage 22 for the fluid. The upper end is threaded 70 for attachment to the sucker rod 23.

The lower end of the head has a shoulder 24 projecting beyond the plunger barrel to contact with the upper end of the gland 10 whose inner surface makes a close fit with the plunger barrel 19. Both the lower end 80 of the gland 10 and the upper end of the sleeve 7 have annular grooves 25 to receive and compress the packing.

In operation the gland 10 will be pressed downwardly upon the packing until it is 85 sufficiently compressed to fit the plunger closely. The slips 13 will thus be allowed to drop by gravity until the teeth thereon engage the teeth 18 on the pump barrel, thus holding the gland in position. If the packing becomes so worn as to necessitate further compression, this may be accomplished by lowering the plunger until the shoulder 90 24 contacts with the gland 10. A few blows of this head upon the gland will drive it 95 downwardly, compressing the packing which will be automatically locked in compressed position by the jaws or slips 13 as previously explained. The plunger may be then raised and the pumping may proceed as before.

The pump may thus be operated for long 100 periods without necessity of renewal of the parts and without removing the plunger from the well. Further objects and advantages will be understood without further 105 description.

What we claim as new and desire to protect by Letters Patent is:

1. In a pump, a pump barrel having an upper section and a lower section constitut- 110

ing a nipple, a packing sleeve in said lower section having an upper radial flange adapted to be clamped between said sections, compressible packing means above said sleeve and a plunger reciprocable in said packing and sleeve.

2. In a pump, a pump barrel comprising a long section and a short section below said long section, said short section being of 10 smaller internal diameter than said long section, a sleeve within said short section, hav-

ing a radial flange engaged between said sections, packing rings in said barrel above said sleeve for the purpose described, a pump plunger and means actuated by said plunger to compress said packing rings against said sleeve.

In testimony whereof we hereunto affix our signatures this 7th day of November, A. D. 1923.

JAMES M. McDONOUGH.
TONY J. STEVENS.
